SYSTEM AND APPARATUS FOR CONTROLLING FLUID-MOTORS.

1,229,543.

Specification of Letters Patent. Patented June 12, 1917.

Application filed October 5, 1912. Serial No. 724,063.

To all whom it may concern:

Be it known that we, NORMAN W. STORER, a citizen of the United States, and ARTHUR J. HALL, a subject of the King of Great Britain, residents, respectively, of Pittsburgh and Wilkinsburg, in the county of Allegheny and State of Pennsylvania, have invented a new and useful Improvement in Systems and Apparatus for Controlling Fluid-Motors, of which the following is a specification.

Our invention relates to systems and apparatus for controlling fluid motors, and it has special reference to power-actuated drum controllers and systems embodying the same.

One object of our invention is to provide a relatively simple and compact mechanism for actuating controllers of the drum type that shall be adapted to replace the usual cover and motormen's handles of present manually operated railway controllers, and the operation of which is governed by a small master controller.

Another object of our invention is to provide a controller actuating device of the character above indicated which shall be so constructed and arranged as to permit of its operation and use, either singly or in multiple with others, for controlling the operation of either single cars or trains composed of any number of cars.

Another object of our invention is to provide a fluid-operated controller drum which may be positively actuated in a series of distinct and definite steps through the agency of an operating cylinder and a movable piston upon the opposite sides of which relatively high balanced pressures are normally maintained for the purpose of holding the piston at rest, it being necessary only to reduce the pressure on one side of said piston in order to effect an unbalancing of pressures and a consequent movement of the piston in the one direction or the other until balanced pressures are restored.

A well known type of controller for railway motors comprises a main drum that is rotatable for the purpose of governing the motor circuits and the value of the accelerating resistance, and a reverse drum that is adapted to occupy the one or the other of two positions, according to the desired direc-

tion of rotation of the motor armatures. The drums are provided with star wheels and pawls or similar devices for accentuating the various control positions, and the drum shafts extend through holes in the cover of the controller so that they may be turned by means of suitable handles. However, cars equipped with controllers of this character cannot be operated in trains and controlled from the front end only, since the controllers must be separately and manually operated.

According to our present invention, we provide what we shall hereinafter term an "operating head" which constitutes a unitary structure that may be removably secured to any ordinary drum controller and is adapted to actuate the main drum of the controller either step-by-step or continuously, and also to operate the reverse drum. The controllers and their associated "operating heads" may be located under the cars, and the operation thereof governed by means of a master controller and a suitable remote-control auxiliary system which may conveniently be of the multiple-unit type.

In a co-pending application, Serial No. 724,065, filed October 5, 1912, by A. J. Hall and L. G. Riley, and assigned to the Westinghouse Electric and Manufacturing Co., a somewhat similar control system is disclosed which embodies a fluid-operated controller drum that is adapted to be actuated through a series of steps in accordance with the manipulation of a master controller, which, in turn, governs the operation of a plurality of electro-magnetically controlled valves that are associated with the opposite ends of an operating cylinder. This fluid-actuated device, however, is so constructed and arranged as to be actuated by merely admitting an operating fluid to one side of its movable piston, and its movement is arrested by releasing the operating fluid and thus permitting the reestablishment of balanced atmospheric pressures acting upon the piston.

An appreciable time interval is necessarily required to effect the exhaust of operating fluid, during which period, the inertia of the moving piston and associated parts may cause it to over-shoot its proper position, while the operating fluid released is entirely

wasted. In order to resume the operation, a complete new charge of fluid is required which becomes effective only when a material pressure has been built up which consumes an appreciable element of time. Moreover, 5 in case it is desired to reverse the direction of operation, it becomes necessary to discharge the fluid from one side of the piston in order to bring it to rest and, subsequently, to 10 admit operating fluid to the opposite side thereof, which results in the loss of a material quantity of operating fluid. Furthermore, a relatively large amount of time is required which renders the operation correspondingly slow and less sensitive. 15 According to our present invention, however, balanced pressures are normally maintained on both sides of the piston and, therefore, movement in either direction may be effected quickly merely by opening the 20 exhaust valve on one side thereof to permit the escape or reduction in pressure of the operating fluid. As soon as the pressure on one side has been reduced a comparatively small amount, the unbalanced pressures acting 25 upon the piston is sufficient to cause the movement thereof. Only a relatively small amount of operating fluid therefore is wasted, while the operation of the apparatus 30 is quickly responsive. In order to arrest the movement of the piston, it is only necessary to supply a small additional amount of operating fluid to the low-pressure side, thereby 35 establishing balanced-pressure relations and positively and definitely bringing the piston to rest. Our present invention, therefore, has the advantages of economy of operating fluid which is utilized at a relatively high average pressure and, therefore, serves 40 to produce a quick and sensitive operation of the control drum which is positively stopped in any position and is substantially "dead beat."

Figure 1 of the accompanying drawings is 45 a plan view, with the cover removed, of a controller operating head which forms a part of our invention. Fig. 2 is a view in side elevation and in section of the operating head of Fig. 1 and the upper portion of 50 a controller with which the head is associated. Figs. 3 and 4 are sectional detail views, on a larger scale, of the valves which form parts of the operating head shown in the other figures. Fig. 5 is a diagrammatic 55 view of the auxiliary control circuits of a system embodying our invention.

A preferred type of complete (main and auxiliary circuit) control system is set forth and claimed in our co-pending divisional application, Serial No. 122,383, filed September 27, 1916, and in the present specification we will describe and explain only such control circuits and connections as are necessary to afford a thorough understanding of our 65 present invention.

Referring to Figs. 1 to 4, inclusive, of the drawings, the structure here shown comprises an operating head 1, a controller of the well known type having a casing 2, a main drum 3, a reversing drum 4, and suitable control fingers associated with each 70 drum.

The operating head 1 comprises a base plate 5, which constitutes the cover of the casing 2, a pair of cylinders 6 and 7, pistons 8 and 9 operating therein, a connecting rod 10 for the pistons having a rack upon one side for actuating the main drum 3 of the controller, electromagnetically actuated valves 11 and 12 for controlling the supply 80 of compressed air to the cylinders 6 and 7, cylinders 13 and 14, pistons 15 and 16, a connecting rod 17 for the pistons 15 and 16 adapted to actuate the reverse drum 4, electromagnetically controlled valves 18 and 19 85 for controlling the supply of compressed air to the cylinders 13 and 14, and a pair of auxiliary or control drums 20 and 21 which are respectively coupled to the drums 3 and 4 of the controller and are provided with suitable 90 contact fingers. The cylinders 6, 7, 13 and 14 may form a single casting or may be separately secured to the base plate 5 upon which they are mounted, and the cylinder heads are preferably formed integral with 95 the valve casings with which they are associated.

A yoke 22 is mounted on the cylinder casting and is provided with bearings 23 and 24 in which a shaft 25 of the auxiliary drum 20 100 is rotatively supported. Another yoke 26 is secured to the cylinder casting and is provided with bearings 27 and 28 in which a shaft 29 of the auxiliary drum 21 is rotatively mounted. 105

The shafts 25 and 29 are respectively in substantial alinement with shafts 30 and 31 of the drums 3 and 4, to which they are operatively connected by couplings 32 and 33. The coupling 33 is provided with a crank 110 projection 34 which is operatively connected to the piston rod 17 by means of a link 35. The arrangement of parts is such that, when the actuating windings of the valves 18 and 19 are energized, compressed air is admitted 115 through the said valves to the cylinders 13 and 14, and, when the said windings are de-energized, the cylinders are open to the atmosphere and the air pressure within them 120 is relieved.

The coupler 32 is provided with an annular toothed portion which constitutes a pinion and meshes with the teeth of the rack upon one side of the connecting rod 10. The arrangement of parts is such that, when fluid 125 pressure is admitted through the valve 11 to the cylinder 6 and fluid pressure is exhausted through the valve 12 from the cylinder 7, the pistons 8 and 9 and the connecting rod 10 are so actuated as to produce rotative 130

movement of the main drum 3 and the auxiliary or control drum 20.

The electromagnetically actuated valves 11, 18 and 19 are substantially alike and each of them is constructed as shown in Fig. 3 of the drawings. The valve 12 is, however, constructed as shown in Fig. 4 of the drawings. Each of the valves 11, 18 and 19 comprises a casting 39 having a vertically extending cylindrical chamber, a pair of apertured disks 37 and 38 having frusto-conical valve seats located and spaced apart within the said chamber, a valve stem 42 having frusto-conical plugs 40 and 41 adapted to engage said seats, and a magnet comprising a coil 43, a stationary core member 44, which forms a part of the casting 39, and a movable core member or armature 45 which is secured to the valve stem 42.

The cylindrical chamber in which the disks 37 and 38 are located is divided thereby into an exhaust chamber 46 having an exhaust port 47, an inlet chamber 48 having an inlet port 49, and a pressure chamber 50 with which a passage 51 leading to the cylinder communicates. The lower end of the valve stem 42 is enlarged to form a frusto-conical spring seat 52, and a plug 53, which closes the lower end of the cylindrical chamber, is provided with an opposing conical projection 54, a helical spring 55, which tends to force the plug 41 against its seat and to raise the plug 40 from its seat, being interposed between the members 52 and 54. When the coil 43 is energized, the armature 45 is moved downwardly to cause the plug 40 to engage its seat and the plug 41 to be released from its seat.

When the plug 40 is raised, the cylinder with which the passage 51 communicates is exhausted through the port 47, and when the plug 41 is lowered, fluid pressure is supplied from any suitable source (not shown) through the inlet port 49.

The magnet valve 12 shown in Fig. 4 differs from that of Fig. 3 in that its exhaust passage is normally closed and its admission passage is normally open. It comprises a casting 56 having a stepped cylindrical chamber which is divided into an exhaust chamber 57, a pressure chamber 58 and an admission chamber 59 by means of apertured disks 60 and 61 having frusto-conical valve seats.

A frusto-conical plug 62 for the exhaust passage cooperates with the seat in the disk 60 and is normally held in engagement therewith by a spring 63, while another plug 64 is, by the same means, normally maintained in a raised position and out of engagement with the corresponding seat in the disk 61. The plugs 62 and 64 are carried by a valve stem 42 that is adapted to be actuated by an electromagnet similar to that shown in Figs. 2 and 3, the plug 62

being lowered away from its seat when the electromagnet is energized and the plug 64 being caused to engage its seat.

In view of the foregoing, it is evident that if the actuating electromagnets of the valves 18 and 19 are both deenergized, atmospheric pressure will exist in the cylinders 13 and 14, and, accordingly, no movement of the pistons 15 and 16 or of the reverser and auxiliary drums 4 and 21 will occur, while if one is energized and the other is deenergized, the pistons, the connecting rod 17 and the link 35 will be moved away from the valve, the electromagnet of which is energized. In order, therefore, to actuate the reverser drum 4 and the auxiliary control drum 21, it is only necessary to energize the actuating winding of the valve in the opposite direction to that which it is desired to move the pistons 15 and 16.

Since the valves 11 and 12 are different in construction, that is, since the valve parts in the one are in inverse relation to those in the other, full pressure will normally exist in the cylinder 7, while pressure will be exhausted from the cylinder 6 when the actuating windings of both magnets are deenergized, and, therefore, the drum 3 and the control drum 20 will be moved into or held in their "off" positions.

In order to advance the said drums, it is only necessary to energize the actuating windings of both the valves 11 and 12, thereby introducing full pressure to the cylinder 6, and exhausting pressure from the cylinder 7. The drums may be stopped and held indefinitely in any position by merely deenergizing the actuating winding of the valve 12, while energy is supplied to the winding of the valve 11, or, in other words, by restoring full balanced pressure in the cylinders 6 and 7.

The auxiliary or control drum 20, as hereinafter pointed out, is adapted to govern the energization of the actuating windings for the valves 11 and 12, while the control drum 21 is adapted to govern the energization of the windings of the reverser valves 18 and 19.

Referring to Fig. 5 of the drawings, the control system here shown comprises a positive supply circuit conductor 71, a negative line conductor 72, a control circuit resistor 78, the auxiliary or control drum 20, which is preferably mounted on the same shaft as the main accelerating drum 3, as fully set forth in our above-identified co-pending application, the reversing auxiliary or control drum 21, a limit switch 79, an overload trip relay switch 80, a main master switch 81 and a reversing master switch 82.

The control circuit resistor 78 is connected directly between the supply circuit conductors 71 and 72, when a pair of switches 83 and 84 are closed.

The master reverser 82 is adapted to oc-

cupy positions x and y and the master switch 81 is adapted to occupy an "off" position and a plurality of motor-operating positions 1 to 8, corresponding to the various 5 positions of the main control drum 3.

Assuming that the master reverser 82 is thrown to position x and that the master switch 81 is moved into position 1, a circuit is established from an intermediate tap 85 10 in the resistor 78, to a conductor 86, contact fingers 87 and 88, which are bridged by a contact member 89, a conductor 90, contact fingers 91 and 92 of the auxiliary reverser drum 21 which are bridged by a contact 15 member 93, actuating coil 94 of the valve 18, a conductor 95, contact fingers 96 and 97, which are bridged by a contact member 98 of the master reverser 82, an emergency cut-out switch 99, a conductor 100, contact fingers 101, which are bridged by a contact member 102, and a conductor marked 0 to substantially the middle point in the control resistor 78.

The coil 94 of the valve 18 being now energized, causes fluid pressure to be admitted 25 to the cylinder 13, with the result that the reverse drum 4 and the auxiliary drum 21 are moved to the position x . In this position, the finger 92 is disengaged from the 30 contact member 93 and, consequently, the coil 94 is deenergized so that fluid pressure is released from the cylinder 13 in order that the reverser may be ready for subsequent operation in the opposite direction.

35 A circuit concurrently is completed from the conductor 90, through contact fingers 103 which are bridged by a contact member 104 when the controller 20 occupies its "off" position, a conductor 105, a coil 106 of the 40 line switch, the trip relay switch 80, a conductor 107, contact fingers 108 and 109, which are bridged by a contact member 110 of the control reverser 21, the conductor 95, etc., to the conductor 0. The line switch is 45 thus closed and a holding circuit is established for the coil 106 from the conductor 90, through the interlocking contact members marked LS—in.

50 As soon as the line switch closes, a circuit is also established from conductor 90 through the interlocking contact members LS—in, actuating coil 115 of the valve 11, and the conductor 107, etc., to the 0 conductor. By reason of the energization of the 55 coil 115 of valve 11, fluid pressure is admitted to the cylinder 6. However, no movement of the pistons 8 and 9 occurs at this time because balanced pressures exist in the cylinders 6 and 7.

60 A connection is concurrently established 65 from the conductor 90 through contact fingers 111 and 112, which are bridged by a contact member 113 of the auxiliary drum 20, a conductor 114, the limit switch 79, the actuating coil 117 of the valve 12, and con-

ductor 107, etc., to the 0 conductor. Fluid pressure is consequently released from the cylinder 7, and the drums 3 and 20 are moved forward until the contact finger 111 becomes disengaged from the member 113. 70 This occurs as soon as control drum 20 occupies position 1. At this point in the operation, the coil 117 of the valve 12 is deenergized, thereby restoring balanced pressures in the cylinders 6 and 7 and holding 75 the drums 3 and 20 in position 1.

The initial series circuit connections of the governed motors are thereupon established by the main controller 3, as will be understood, and as fully set forth in our 80 above-identified divisional application.

The acceleration of the motors will not progress so long as the master switch 81 remains in position 1, but if the master switch is moved successively through its positions 2, 85 3 and 4, the coil 117 of the valve 12 is alternately energized and deenergized, and the drums 3 and 20 will move forward through the corresponding positions step-by-step, but dependent upon the action of the limit 90 switch 79, in accordance with a familiar principle. Thus the resistance of the motor circuit is gradually eliminated, thereby causing the motors to accelerate in speed. If the motor current exceeds the value for which 95 the limit switch is adjusted, further progression of the controller is prevented because of the interruption of the energizing circuit of coil 117 of valve 12 which causes the admission of pressure to cylinder 7 and 100 holds the controller drum at rest. As soon as the current falls and permits the limit switch 79 to close, coil 117 is again energized and the valve 12 exhausts cylinder 7 and allows the piston 8 to advance the controller 105 to its next step. Subsequently, the operation may proceed in accordance with circuit conditions and the will of the operator.

The controller 3 is adapted to effect a 110 well known series-parallel control for the motors and need not be described in detail. As to the controller 20, the contact member 113 is so subdivided and arranged as to interrupt the circuit established through the coil 117 of the magnet valve 12 as each control position is reached. Each successive forward movement is thus dependent both upon the limit switches and the position of the master controller.

The contact member 102 is mounted on an 115 insulating ring 152 that is connected to the drum of the master controller 81 by a friction clutch or similar connection and is limited in its rotative movement by a stationary pin or stop 153 which permits it to move 120 only into engagement with the fingers 101. The arrangement of parts is such that when the master switch is moved into its position 1, the friction clutch connection carries the 125 contact member 102 into engagement with 130

the fingers 101 and the stop 153 holds it in this position as long as the master switch progresses forwardly, but any backward movement of the master switch, whether it be from the position 8 or from some intermediate position, will move the contact member 102 out of engagement of the fingers and will break the circuit at this point.

From the circuits above traced, it is evident that, as soon as the circuit is interrupted between the fingers 101, the line switch will be opened and the coils of the valve 11, 12, 18 and 19 will be deenergized. While this will produce no movement of the reverser 21, it will throw the drums 3 and 20 to their off positions, as hereinbefore pointed out.

Obviously, the circuit connections of the system may be varied considerably and the operating head may also be greatly modified as to its structural features and may be employed to operate any form of drum controller or regulator, without departing from the spirit and scope of our invention, and we, therefore, do not wish our invention limited to the specific details herein disclosed.

We claim as our invention:

1. The combination with a fluid actuator comprising a cylinder and a piston movable therein, of means for admitting fluid to one end of the cylinder and for releasing it at the other end to effect forward movements of the piston, and for admitting fluid to both ends of the cylinder to stop the said forward movement and to maintain the piston stationary, said means being adapted to normally bias said piston to its initial position.

2. The combination with a fluid actuator comprising a cylinder and a piston movable therein, of means for admitting fluid to one end of the cylinder and for releasing it at the other end to effect forward movements of the piston, and for admitting fluid to both ends of the cylinder to stop the said forward movement and to maintain the piston stationary, said means being caused to release fluid from one end of the cylinder and to admit fluid to the other end thereof in order to bias the piston to one of its extreme positions.

3. The combination with a fluid-actuator comprising a cylinder and a piston movable therein, of valves governing the admission and release of fluid to and from the respective ends of the cylinder, electromagnets for respectively actuating the said valves, and means governing the circuits of the electromagnets whereby one thereof is continuously energized to admit fluid to one end of the cylinder, and whereby the other is energized to release fluid from the other end thereof to permit a forward movement of the piston and is deenergized to stop the said forward movement, both electromagnets being deenergized to return the piston to its initial position.

4. The combination with a fluid-actuator comprising a cylinder and a piston movable therein, of valves governing the admission and release of fluid to and from the respective ends of the cylinder, electromagnets for respectively actuating the said valves, and means governing the circuits of the electromagnets whereby one thereof is continuously energized to admit fluid to one end of the cylinder, and whereby the other is energized to release fluid from the other end thereof to permit a forward movement of the piston and is deenergized to stop the said forward movement.

5. The combination with a fluid actuator comprising a cylinder and a coöperating movable piston, of means for admitting fluid to one end of said cylinder and for releasing it from the other end thereof to effect a movement of said piston in one direction and for subsequently admitting fluid to the second end of said cylinder to arrest the movement of said piston, said means being adapted to bias said piston to its initial position.

6. The combination with fluid actuating means comprising a movable member and a container in which it is disposed, of means for admitting an operating fluid to one end of said container and for releasing it from the other end thereof for effecting a movement of said movable member in one direction, for admitting operating fluid to both ends of said container for arresting the movement of said piston and maintaining it at rest, and for releasing operating fluid from the first end of said cylinder and admitting it to the second end thereof for effecting a movement of said piston in the opposite direction, said means being adapted to bias said piston to its initial extreme position.

7. The combination with a rotatable member, of an operating head comprising a control drum and a gear pinion operatively connected with the rotatable member, a rack meshing with the pinion, and electro-pneumatic actuating means for adjusting the rack.

8. The combination with a rotatable member, of an operating head comprising a control drum and a gear pinion operatively connected with the rotatable member, a rack meshing with the pinion, a pair of pistons secured to opposite ends of the rack, cylinders in which the pistons operate, and electrically controlled valves for governing the admission of operating fluid to the cylinders.

9. The combination with a rotatable member, of a fluid-operated head comprising a control drum, a gear pinion operatively connected with the rotatable member, a rack meshing with the pinion, pistons secured to

- opposite ends of the rack, cylinders in which the pistons operate, and electro-magnet valves associated with the cylinders, one of said valves being closed when energized to 5 exhaust fluid from its associated cylinder and the other being open when energized to admit fluid to the cylinder with which it is associated.
10. The combination with a casing, a rotatable member and a shaft for said member extending upwardly out of the casing, of means removably mounted on the casing, comprising a pair of pistons, cylinders in which the pistons operate, an operative connection between the pistons and the shaft 15 of the member, and electro-responsive means for governing the admission of operating fluid to the cylinders.
11. A fluid actuator comprising a cylinder and a piston movable therein, and means for admitting operating fluid to one end of the cylinder and for releasing it from the other end thereof to effect movements of said piston and for admitting operating fluid to both ends of said cylinder to arrest the movements thereof, said means being adapted to bias said piston to a predetermined position.
12. The combination with fluid-actuated means comprising a cylinder and a piston movable therein, of valves for governing the admission and release of operating fluid to and from the respective ends of the cylinder, electro-magnets for respectively actuating said valves and means governing the circuits of said electro-magnets whereby one electro-magnet is continuously energized to admit operating fluid to one end of the cylinder which fluid tends to actuate said piston in one direction and whereby the other electro-magnet is energized to release operating fluid to permit movements of said piston.
13. The combination with fluid-operated means comprising a cylinder, a piston disposed therein, and a plurality of valves severally associated with the opposite ends of said cylinder for governing the admission and release of operating fluid to and from said cylinder, one of said valves being normally closed and the other normally open whereby unbalanced pressures bias said piston to one of its extreme positions, of control means for opening said first valve to effect a balance of pressures acting upon said piston and for closing said second valve whereby the pressure in the corresponding end of the cylinder is released and the resultant unbalance of pressures upon the piston effects a movement thereof away from its initial position.
14. The combination with fluid-operated means comprising a cylinder and a piston disposed therein, of a plurality of valves associated with the opposite ends of said cylinder for governing the admission and release of operating fluid to and from the
- respective ends thereof and adapted to establish unbalanced pressures acting upon said piston to actuate said piston in a forward direction, to establish balanced pressures to arrest the movement of said piston 70 and to effect reversed unbalanced pressures to actuate said piston in the opposite direction.
15. The combination with fluid-operated means comprising a cylinder, and a piston disposed therein, of a plurality of valves associated with the opposite ends of said cylinder for governing the admission and release of operating fluid to and from the respective ends thereof, one of said valves 75 being normally open and the other valve being normally closed, and control means for maintaining said second valve open and for intermittently closing said first valve to effect step-by-step movements of said piston. 80
16. The combination with fluid-actuated means comprising a cylinder and a movable piston, of a plurality of electro-magnetically controlled valves disposed at the respective ends of said cylinder for governing the admission and release of operating fluid, one 90 of said valves being open and the other closed when deenergized whereby unbalanced pressures act upon said movable piston for biasing it to a predetermined position, and control means including means dependent upon the position of said piston for continuously energizing the second electro-magnetically controlled valve and intermittently energizing the first electro-magnetically controlled valve whereby a step-by-step movement of said piston is effected. 95
17. The combination with fluid-actuated means comprising a cylinder and a movable piston associated therewith, of a plurality 100 of electro-magnetically controlled valves disposed at the respective ends of said cylinder for governing the admission and release of operating fluid, one of said valves being normally open and the other closed, of control means including an auxiliary controller mechanically associated with said piston and having interlocking control means adapted to make and break the energizing circuit of the first electromagnetically controlled valve 110 and also for maintaining the energization of the second electro-magnetically controlled valve. 115
18. The combination with a fluid-actuator comprising a fluid-containing member and a movable member disposed therein, of valves for governing the admission and release of fluid to and from the respective ends of said containing member, electrically controlled means for actuating said valves, and means for governing the circuits of said electrically controlled means whereby one of said means is continuously energized to admit fluid to one end of said containing means and whereby the other is energized to release 120
- 125
- 130

fluid from the other end of said containing means to permit a forward movement of said movable means and is deenergized to arrest said forward movement.

- 5 19. The combination with a fluid-actuated mechanism comprising a piston and a cylinder in which the piston operates, of means for continuously supplying operating fluid to one side of the said piston, and means 10 under the control of an operator for governing the admission of operating fluid to the other side of said piston in accordance with the position thereof for effecting a definite step-by-step movement thereof.
- 15 20. The combination with a fluid-actuated mechanism comprising a piston and a cylinder, of means for continuously admitting an operating fluid to one end of said cylinder and for admitting and releasing operating 20 fluid to and from the opposite end thereof, said means embodying means associated with said piston for effecting the successive admission and release of operating fluid to and from the last named end of said cylinder, whereby predetermined distinct steps in 25 the movement of said piston are effected.
21. The combination with a fluid-containing member and a movable member disposed therein, of controllable valves for governing 30 the fluid pressure in the respective ends of said containing member, one of said valves being normally opened and the other closed whereby said movable member is biased to one position, and means for holding open 35 the closed valve and intermittently closing the open valve to effect a step-by-step movement of said movable member in a forward direction.
22. The combination with a fluid-actuator 40 comprising a fluid-containing member, a movable member disposed therein, and electrically-controlled valves for governing the admission and release of operating fluid to and from the respective ends of said containing member, of controlling means comprising a master controller and an auxiliary controller for governing the circuits of said electrically controlled valves, whereby one 45 of said valves is continuously energized to admit fluid pressure to one end of said containing member and the other is concurrently energized to permit a forward movement thereof and is deenergized to arrest 50

said forward movement, said auxiliary controller being connected in circuit with one 55 of said electrically controlled valves for effecting a step-by-step movement of said movable member.

23. The combination with fluid-actuated means comprising a cylinder and a piston 60 movable therein, of controllable valves for governing the fluid pressure in the respective ends of said cylinder, means for holding open one of said valves to continuously admit operating fluid to one end of said 65 cylinder, and for intermittently closing the other valve to release operating fluid from the other end thereof whereby said piston is actuated in a series of distinct steps.

24. The combination with fluid-actuated 70 means comprising a cylinder and a piston disposed therein, of a plurality of valves associated with the opposite ends of said cylinder for governing the admission and release of relatively high-pressure operating 75 fluid to and from the respective ends thereof, and adapted to normally admit high-pressure fluid to one end of said cylinder to bias said piston to its off position, to admit high-pressure fluid to the other end of said 80 cylinder and to release operating fluid from the first end thereof to effect a forward actuation of said piston, and to admit high-pressure fluid to both ends of said cylinder to arrest movements thereof. 85

25. The combination with a fluid-actuator comprising a cylinder and a piston disposed therein, of means for normally establishing atmospheric pressure in one end of said cylinder and a relatively high pressure in the 90 other end thereof to bias said piston to one extreme position, for establishing a reversed condition of relative pressures upon the respective sides of said piston for effecting its actuation in the opposite direction and for 95 establishing balanced high pressures in both ends of said cylinder to arrest movements thereof.

In testimony whereof, we have hereunto subscribed our names this 4th day of Oct., 100 1912.

NORMAN W. STORER.
ARTHUR J. HALL.
